ATTACHMENT FOR HAIR WAVING
MACHINES

Edna L. Frantz, Slatington, Pa.

Application August 24, 1937, Serial No. 160,692

2 Claims. (Cl. 132—36)

This invention relates broadly to permanent hair waving machines and more particularly to an attachment therefor for relieving the head of the patron of the weight of the electrical heating element and the electric wires connected thereto; and the invention together with its objects and advantages will be best understood from a study of the following description taken in connection with the accompanying drawings wherein:

10 Figure 1 is a side elevational view of an electric permanent hair waving machine illustrating the application of the invention thereto.

Figure 2 is a top plan view of the machine.

Figure 3 is a bottom plan view of the attachment, and

Figure 4 is an end elevational view of the attachment.

Referring to the drawings by reference numerals it will be seen that 5 indicates generally a conventional electric permanent hair waving machine, and more specifically the well-known standard "Bonat" waving machine, which latter includes among other parts a base 5 having a longitudinally adjustable standard 6 arising therefrom on which is mounted the bracket 7 supporting the machine proper. The machine proper, indicated by the reference numeral 8 includes among other parts electrical plugs 9 from which lead wires 10. Attached to the lower or free ends of the wires 10 are the electrical heaters 11 which are applied to the hair of the patron in the process of permanently waving the hair of the patron.

The invention per se is in the form of a support 12 that is mounted on the bottom side of the machine 8 and consists, in the present instance, of an elongated channel member 13 the sides of which are provided with outstanding integral hooks 14.

Intermediate its ends the member 12 is provided with an opening 15 to accommodate a bolt or other suitable fastening element 16 through the medium of which the attachment 12 is secured to the under side of the machine to extend diametrically thereof.

The projections 14 integral with the sides of the channel member 13 are in the form of hooks with which the wires 10 are engaged by being wrapped therearound to an extent sufficient to so suspend the heating elements 11 from the attachment 12 as to relieve the head of the patron from the combined weight of the heating elements 11 and the wires 10.

While the hooks 14 may be arranged as found desirable, it will be noted that at the present instance a longitudinal series of seven hooks extend from each side of the member 13 and include a series of three hooks the bills of which curve in one direction and a second series of three hooks

the bills of which curve in a direction facing the bills of the first mentioned series of hooks together with an intermediate hook 14'. In this connection it will be noted that the bill of the hook 14' on one side of the device 13 faces in a direction opposite to the bill of the hook 14' on the opposite side of the member 13.

Such an arrangement has been found to be most convenient for engaging the wires 10 at opposite sides of the machine with the said hooks, it being understood that the wires are wrapped about the hooks so that the wires are held comparatively taut to the end that the weight of the wires and the electrical heating elements on the free ends of the wires is relieved from the head of the patron.

Thus it will be seen that with this attachment the major portion of the weight of the heating element is carried by the attachment to the greater comfort of the patron in the application of the hair waving process with the result that the operator of the permanent hair waving machine may administer the permanent wave with greater facility and efficiency.

It will also be understood that the holder 12 may be formed of metal or other suitable material.

It is thought that a clear understanding of the construction, utility and advantages of a hair waving machine attachment of the character embodied in the present invention may be had without a more detailed description.

Having thus described the invention what is claimed as new is:—

1. In combination with an electric permanent hair waving machine including a circular head having electric wires extending downwardly from the periphery thereof and heating elements electrically connected with the free ends of said wires, a supporting member mounted diametrically on said head at the under side thereof and provided at opposite sides with laterally extending projections positioned inwardly of the marginal edges of the head with which said wires are engaged in a manner to center the heating elements over the head of the patron and to relieve the weight of the wires and the heating elements from the head of the patron.

2. An attachment for electric permanent hair waving machines comprising a channel-shaped member adapted to be bolted to the under side of the machine to extend transversely thereof and having a series of suspension hooks extending laterally from opposite sides thereof for supporting and centering the heating elements of the machine over the head of the user.

EDNA L. FRANTZ.
